UNITED STATES PATENT OFFICE.

JOHN M. MORAN, OF SEATTLE, WASHINGTON.

RADIATOR SHIELD.

Application filed December 4, 1924. Serial No. 753,770.

To all whom it may concern: -

Be it known that I, JOHN M. MORAN, a citizen of the United States, residing at Seattle, in the county of King and State of Washington, have invented a certain new and useful Improvement in Radiator Shields, of which the following is a specification.

My invention relates to radiator shields and the object of my invention is to provide a radiator shield having a sectional back portion whereby it may be readily installed on steam or hot water radiators of the form that are supported by brackets that extend outwardly from the wall, the parts of said sectional back portion being slotted to fit over the brackets that support the radiator in such a manner that the heated air cannot pass upwardly between the wall and the radiator.

Another object is to provide a radiator shield having detachable end plates that are slotted to fit over pipes that may be connected with the ends of the radiator and that have means for closing the slots that fit over the pipes.

Another object is to provide a radiator shield of inexpensive, simple and efficient construction and is so shaped that it may be interposed between an ordinary steam or hot water radiator and an adjacent wall and will extend up and over the top of the radiator to deflect heated air outwardly and to prevent contact of such heated air with the wall thereby better distributing the heated air into a room and protecting the wall from excess heat and from the well known blackening effect that occurs on the wall behind and above the radiator.

I accomplish the above objects by devices illustrated in the accompanying drawings, wherein—

Figure 1 is a perspective view of a radiator showing my shield disposed thereon;

Fig. 2 is a sectional view of the same on a larger scale on broken line 2, 2, of Fig. 1;

Fig. 3 is a detached view in front elevation of the radiator shield; and

Fig. 4 is a fragmentary perspective view showing a means for closing a slot on an end plate of the shield.

Referring to the drawings, throughout which like reference numerals indicate like parts, I have shown a radiator shield embodying a normally vertical back portion comprising an upper section 5 and a lower

section 6. The upper section 5 is connected by an integral curved portion 7 with a top portion 8 that is inclined at an angle of more than ninety degrees relative to the back portion 5 so that when the shield is placed upon a radiator 9 with the back portion extending vertically between the radiator and an adjacent wall 10 the top portion 8 will extend outwardly over the top of the radiator in upwardly inclined relation relative to the horizontal.

The top portion 8 is provided at the front edge with a roll 11 formed by bending the same downwardly and inwardly throughout substantially three fourths of one complete revolution thereby leaving, on the inner side, an opening 12 through which dust that is carried by ascending currents of heated air may enter a dust trap 13 that is formed within such roll. A dust absorbent packing 14 is provided within the dust trap 13.

L-shaped brackets 15 of angular cross-sectional shape are provided at the ends of the shield and cooperate with the rolled portion 11 to form a rigid and substantial shield structure.

The back portion of the shield is made up of the upper section 5 and the detachable lower section 6 which cooperate to facilitate the installation of the shield on radiators 9 of the form that are supported by brackets 16 that extend outwardly from the wall behind such radiator. The upper back portion 5 may be permanently secured to the L-shaped end brackets 15, as with rivets 17, but the lower back section 6 is detachably secured to said brackets 15, as by screws or bolts 18.

The lower edge of the upper back section 5 is provided with upwardly extending notches 20 and the upper edge of the detachable back section 6 is provided with corresponding downwardly extending notches 21 that register with the notches 20 and fit over the supports 16 when the shield is installed.

In installing the shield the lower back section 6 is first detached from the end brackets 15, the shield is then lowered into position from above with the notches 20 fitting over the brackets 16 and the lower back section 6 is then slipped up over the brackets 16 from below and secured to the end brackets 15 by means of the bolts 18.

If desired, clamp hooks 22 may be used further to anchor the shield to the radiator.

Supports 23 that offer little resistance to the outward passage of heated air are provided on the top portion 8 of the shield and are arranged to rest upon the top of the 5 radiator 9.

The lower back section 6 is bent rearwardly at its bottom edge to form a deflector 24 within the extremity of which is secured a packing strip 25 of felt that makes contact 10 with the wall 10.

Detachable end plates 26 are provided at the ends of the shield to cover the ends of the radiator when said radiator is placed in close proximity to a side wall. These end 15 plates 26 are notched at their top edges, as at 27, to permit the passage therethrough of pipes 28 that may be connected with the radiators and the notches 27 are provided with slidably attached plates 29 that close 20 any excess space around a pipe 28 or that

substantially close the notches 27 where there are no pipes to project therethrough.

What I claim is:

In a radiator shield a top portion arranged to extend over the top of a radiator, 25 a back portion arranged to extend downwardly behind a radiator, said back portion being formed of an upper section and a lower detachable section arranged to overlap said upper section and having notches af- 30 fording passageways through which radiator supports may extend and a flexible wall engaging deflector member extending outwardly and downwardly from the bottom edge of said lower detachable section. 35

In witness whereof, I hereunto subscribe my name this 20th day of November A. D. 1924.

JOHN M. MORAN.
